UNITED STATES PATENT OFFICE

FREDERIC C. HOOD, OF BECKLINE, MASSACHUSETTS, ASSIGNEE, BY MESNE ASSIGNMENTS, TO HOOD RUBBER COMPANY, INC., OF WILMINGTON, DELAWARE, A CORPORATION OF DELAWARE

BUCKLE

Application filed April 16, 1929. Serial No. 355,542.

This invention relates to an improved buckle adapted for use on footwear and particularly on overshoes. One embodiment of my invention is illustrated in Figs. 1 to 6 inclusive and another embodiment of my invention is illustrated in Figs. 7 to 12 inclusive. In the embodiment of my invention illustrated in Figs. 1 to 6 inclusive, the upper is provided with a pair of oppositely disposed front edge portions, one overlapping the other, and this upper is preferably constructed of a pair of layers of sheet material, and the buckle is so constructed that the two parts thereof may be positioned between the layers of the oppositely disposed edge portions of the upper, one of them comprising a plate with a hook or hooks projecting therefrom, this plate being positioned preferably between the two layers of the overlapping edge portion of the upper with the hooks thereon projecting inwardly through the inner layer of said overlapping portion, while the other part of the buckle consists of a plate which is positioned between the two layers of the other front edge portion of the upper, or the underlying portion thereof, and this part of the buckle has a raised portion with an orifice or orifices therein which projects through the outer layer of the two layers of which said edge portion is composed.

It is preferred to have a plurality of hooks on one part of the buckle and a single orifice on the other part of the buckle, but it is evident that without departing from the spirit of the invention, a pair of hooks may be provided on one part of the buckle and a plurality of orifices on the other part of the buckle, or a single hook may be provided on one part of the buckle and an orifice or orifices on the other part of the buckle. By having a pair of hooks and a single orifice, or a pair of hooks and a pair of orifices, or a single hook and a pair of orifices, the buckle parts may be adjusted one relatively to the other so that the overlapping front edge portion may be adjusted relatively to the underlying front edge portion of the upper.

It is understood, therefore, that the inven-

tion is not confined to any number of hooks or any number of orifices, but consists of the invention hereinafter described in the specification and particularly pointed out in the claims. Other details of construction or modifications in the different parts comprising the entire buckle are hereinafter more specifically pointed out in the specification, such, for example, as the manner in which the parts of the buckle are securely anchored in their respective portions of the upper.

The embodiment of my invention illustrated in Figs. 7 to 12 inclusive is adapted for use on footwear, and particularly on overshoes, in which the opposite edges of the quarter are joined together by a strap projecting over the vamp. The buckle illustrated in Figs. 7 to 12 inclusive is, however, substantially the same as the buckle illustrated in Figs. 1 to 6 inclusive, except that in Figs. 1 to 6 inclusive the parts of the buckle are attached directly to the upper, while in the embodiment of my invention illustrated in Figs. 7 to 12 inclusive, one portion of the buckle is attached to the upper and the other is adjustably mounted upon the strap.

The buckle of this invention is an improvement upon a buckle for which I have made application for Letters Patent, Serial No. 340,585, filed February 16, 1929.

Referring to the drawings:

Figure 1 is a perspective view of a portion of an overshoe illustrating one embodiment of my invention attached thereto.

Fig. 2 is an enlarged sectional view taken longitudinally through the upper and the buckle, when the buckle parts are joined together.

Fig. 3 is a perspective view on an enlarged scale of one part of the buckle as viewed from the rear side thereof.

Fig. 4 is a perspective view on an enlarged scale of the other part of the buckle viewed from the front side thereof.

Fig. 5 is a perspective view on an enlarged scale of a modified form of my invention embodying therein a single hook.

Fig. 6 is a perspective view on an enlarged scale of a modified form of my invention em-

bodying therein a pair of orifices for receiving a pair of hooks or a hook.

Fig. 7 is a perspective view of a portion of an overshoe illustrating the buckle of my invention attached thereto.

Fig. 8 is an enlarged sectional view taken on the line 8-8 of Fig. 7 and viewed in the direction of the arrows on said line.

Fig. 9 is a perspective view on an enlarged scale of one part of the buckle, as viewed from the rear side thereof.

Fig. 10 is a perspective view on an enlarged scale of the other part of the buckle viewed from the front side thereof.

Fig. 11 is a perspective view on an enlarged scale of a modified form of the hook portion of my invention.

Fig. 12 is a perspective view on an enlarged scale of a modified form of my invention embodying therein an orifice for receiving a hook.

Like numerals refer to like parts throughout the several views of the drawings.

The buckle of this invention as illustrated in Figs. 1, 2, 3 and 4 comprises two parts, one of the parts 8 particularly illustrated in Fig. 3, embodies a plate 9 with two hooks 10 and 11 thereon preferably integral therewith and projecting from the rear face of the plate 9. Commercially, this part of the buckle is struck up from sheet metal. The hooks 10 and 11 each comprises a shank 12 and a prong 13, the inner face 14 of each of said prongs being preferably formed on a concave curve inclined away from the rear face of the plate 9 and the end 15 of each of said prongs being rounded to assist in the insertion of the hooks in the orifices of the other part of the buckle, and also to assist in drawing the two parts of the buckle together when they are in operative position or when the hooks are being inserted in the orifice.

The plate 9 is provided with a slot 16 at one end thereof through which a stay tape 17, preferably adhesive tape, is inserted and the two ends thereof pressed together between the inner layer 18 and the outer layer 19 of the upper 20, said upper being constructed with a pair of oppositely disposed front edge portions 21 and 22, the portion 21 overlapping the portion 22 when the front edge portions are buckled together. The upper has a collar 23 thereon which, when the shoe is being worn, completely covers the buckle. In the drawings, Fig. 1, this collar is shown turned upwardly at 24 for the sake of clear illustration.

The other part 25 of the buckle, particularly illustrated in Fig. 4, comprises a plate embodying two end flanges 26 and 27 with slots 28 therein and a raised central portion 29 which is joined to the flanges 26 and 27 by shoulders 30, 31 and 32. The raised portion 29 is provided with an orifice 33, the ori-

fice being V-shaped and having sides 34 and 35 converging toward the front end of the raised portion 29. This orifice is prolonged rearwardly at 36 between the shoulders 31 and 32. The part 25 of the buckle is fastened in position in the underlying front edge portion 22 of the upper by inserting the flanges 26 and 27 between the inner layer 18 and the outer layer 19 of the underlying front edge portion of the upper 20 as illustrated in Fig. 2, and the part 25 is firmly held in position by means of strips of adhesive tape 37 and 38 which project through the slots 28 and the two ends of the tape are pressed together between the layers 18 and 19 of the upper.

The two parts of the buckle are joined together for use as particularly illustrated in Fig. 2, the hook 11 projecting through the orifice 33 with its front inclined inner face 14 bearing against the forward end of said orifice 33. If desired to draw the overlapping portion 21 of the upper tighter about the foot of the wearer, then the hook 11 is withdrawn from the orifice 33 and the hook 10 inserted therein. It will be evident that instead of having two hooks on the hook portion of the plate 8 a single hook 39 may be formed upon a plate 40 as illustrated in Fig. 5 and this form of the hook portion of the buckle may be used with a plate such as 25 with a single orifice, or it may be used with a plate 41, Fig. 6, which is provided with two hook-receiving orifices 42 and 43. The plate 40 is provided with a slot 44 to receive a stay tape and the plate 41 is provided with a pair of orifices 45 to receive stay tapes.

A still further variety of adjustment may be obtained by spacing the hooks 10 and 11 of Fig. 3 farther apart than the front ends of the orifices 42 and 43. By this difference in spacing between the hooks and the front ends of the orifices an additional adjustment is made possible. For example, in such a case one adjustment is made by inserting the hook 10 in the orifice 42; another adjustment by inserting the hook 10 in the orifice 43; another adjustment by inserting the hook 11 in the orifice 42; and a fourth adjustment by inserting the hook 11 in the orifice 43. No two hooks will bottom in two of the orifices at the same time.

During the operation of attaching the two parts of the buckle to each other, the bevelled inclined inner face 14 of the hook portion engages the inner face of the raised portion of the buckle part which has the orifice therein and thus the hook portion of the buckle and the orifice portion of the buckle are drawn closely together as seen in Fig. 2. Also, as the hooks are drawn up into the V-shaped orifice or orifices, the opposite edges of said orifices will bear against the shanks of the hooks and hold the two parts firmly engaged one with the other.

Furthermore, it will be seen that it is not

necessary in positioning the hooks within the orifice or orifices to be very exact about such a positioning operation as the hook may enter the orifice 33 or 43 through the enlarged rear end portion thereof and then the hook or hooks drawn forwardly.

It will also be seen that there is considerable space between the hooks and the opposite edges of the orifices at the rear ends thereof so that it is very easy to engage the two parts of the buckle, one with the other, and as this operation is performed while the user is leaning over, this is an essential and very desirable feature of the invention, especially as it is impossible for the user to see the orifice at this time due to the same being covered by the portion 21 of the upper. The parts of the buckle of this invention are not only easily connected together but they are also easily disconnected from each other when the user pulls upon the overlapping portion 21 of the shoe upper, due to the inner face 14 of the hook being inclined away from the plate 9.

The buckle of this invention, as illustrated in Figs. 7, 8, 9 and 10, comprises two parts. One of the parts 108 particularly illustrated in Fig. 9, embodies a plate 109 with two hooks 110 and 111 preferably integral therewith and projecting from the rear face of the plate 109. The hooks 110 and 111 each comprise a shank 112 and a prong 113, the inner face 114 of each of said prongs being inclined and the end 115 of each of said prongs being rounded to assist in the insertion of the hooks in the orifices of the other part of the buckle, and also to assist in drawing the two parts of the buckle together when they are in operative position, or when the hooks are being inserted in the orifices. The plate 109 is provided with slots 116 at its opposite ends through which a strap 117 projects as illustrated in Fig. 7. The strap 117 is fastened at one end to the inner portion of a quarter 118 and the plate 109 is adjustable on the strap 117.

The other part 119 of the buckle, particularly illustrated in Fig. 10, comprises a plate embodying two end flanges 120 and 120' and a raised central portion 121 which is joined to the flanges 120 and 120' by shoulders 122, 123 and 124. The raised portion 121 is provided with orifices 125 and 126, the orifices being V-shaped and having sides 127 and 128 respectively which converge toward the front end of the plate 119. The orifice 126 is prolonged rearwardly at 129 between the shoulders 122 and 123. The part 119 is fastened to the quarter 118 by rivets 130 as illustrated in Fig. 8.

The two parts of the buckle are joined together for use as particularly illustrated in Fig. 8, the part 108 being mounted on the strap 117. The strap 117 is drawn across the vamp 131 as illustrated in Fig. 7, and in

this particular illustration of the relative position of the hooks and orifices, the hook 110 is illustrated as projecting into the orifice 125 with its front inclined inner face bearing against the forward end of said orifice. At this time the hook 111 projects into the rear end 129 of the orifice 126, but there is a space between the front face 114 of the hook 111 and the front end of the orifice 126.

The strap may now be adjusted, if desired, in either direction to tighten or loosen the same. For example, if it is desired to tighten the strap 117, the hook 110 is withdrawn from the orifice 125 and inserted in the orifice 126 with its front face 114 bearing against the front end of said orifice 126, or the strap may be loosened by withdrawing the hook 110 from the orifice 125 and allowing the hook 111 to be moved forwardly until it bottoms in the front end of the orifice 126.

The strap may be still further loosened by withdrawing the hook 111 from the orifice 126 and inserting it in the orifice 125 with its front face bearing against the front end of said orifice 125, thus four adjustments are obtained by the construction shown.

If the hooks 110 and 111 were positioned on the plate 109 so that the distance between the front faces 114 of said hooks at that portion thereof which bears against the front end of the orifices were equal to the distance between the front ends of the orifices, then only three adjustments could be made, but by making the distance between the hooks and the distance between the front ends of the orifices different, an additional adjustment is made possible.

During the operation of attaching the two parts of the buckle to each other, the bevelled inclined inner face 114 of the hook engages the inner face of the raised portion 121 of the part 119 and thus the plate 109 and the raised portion 121 are drawn closely together as seen in Fig. 8. Also as the hooks are drawn up into the V-shaped orifices, the opposite edges of said orifices will bear against the shanks of the hooks and hold the two parts firmly engaged one with the other.

In Fig. 7 the overshoe is illustrated as having a collar 132 which, in the illustration, is shown turned up at 133 for the purpose of disclosing the buckle and strap, but when in use the portion 133 of the collar is turned down and covers the buckle and the portion of the strap 117 adjacent thereto.

In the form of my invention hereinbefore described, the parts of the buckle have a plurality of hooks and a plurality of orifices. It is evident, however, that the part 109, with the pair of hooks thereon, may be used in connection with a part 119', Fig. 12, of a buckle constructed like the part illustrated

in Fig. 10, except that only a single orifice 126' is embodied therein.

It is also evident that a part of a buckle 134, Fig. 11, may be employed with a single hook 110' thereon in conjunction with a part like the part 119, Fig. 10.

In both of these modified forms of the invention, Figs. 11 and 12 inclusive, the adjustment of the parts of the buckle relative-
10 ly to each other is preserved, although not to such a great variety and extent as in the case where a plurality of hooks are provided on one part of the buckle and a plurality of orifices on the other part of the buckle.
15 For example, assuming the part 134 with its single hook 110' to be used in conjunction with the part 119 with its two orifices 125 and 126, the hook 110' can be inserted in either one of these orifices, thus providing a means
20 for tightening or loosening the strap 117. It is also evident that if the part 108 of the buckle is used in connection with the part 119', either one of the hooks 110 or 111 may be inserted in the orifice 126' and thus ren-
25 der it possible to adjust the strap 117.

In all of the forms of hooks hereinbefore described it will be understood that the inner faces of the hooks are formed upon a concave curve inclined away from the rear
30 face of the plate to which they are fastened or upon which they are formed. This curve 14 is formed of such a radius and positioned at such an inclination that when it is desired to disconnect the hook portion of the buckle
35 from the portion having the orifice therein, an outward pull upon the portion of the upper or upon the strap to which the hooked plate is connected will cause the hook portion of the buckle to be disconnected from the
40 other portion of the buckle, thus rendering the operation of disconnecting one part of the buckle from the other very easy, while at the same time the two parts of the buckle are so constructed that they will not become
45 accidentally detached one from the other.

I claim:

1. A buckle in two parts, one of said parts embodying a plate formed with a pair of orifices therein, the other of said parts embodying a plate having a pair of hooks projecting from one face thereof each adapted to be bodily inserted in either of the orifices and to be engaged with an adjacent wall of either of said orifices, the distance between engaging portions of said hooks being different from the distance between the hook-engaging walls of said orifices.

2. A buckle in two parts, one of said parts embodying a plate formed with a raised portion, a flange, and a shoulder connecting the flange and raised portion, a pair of orifices formed in said plate, one of which is formed at the shoulder and extends into the raised portion, the other of said parts embodying a

plate having a pair of hooks projecting from one face thereof each adapted to be bodily inserted in either of the orifices and to be engaged with an adjacent wall of either of said orifices, the distance between engaging portions of said hooks being different from the distance between the hook-engaging walls of the orifices. 70

In testimony whereof I have hereunto set my hand.

FREDERIC C. HOOD.
